UNITED STATES PATENT OFFICE

153,899

DESIGN FOR A SPEAKER HOUSING

Robert F. Poorman, Montgomery County, Ohio

Application August 23, 1947, Serial No. 141,033

Term of patent 14 years

(Cl. D26—14)

To all whom it may concern:

Be it known that I, Robert F. Poorman, a citizen of the United States, residing near Dayton, in the county of Montgomery and State of Ohio, have invented a new, original, and ornamental Design for a Speaker Housing, of which the following is a specification, reference being had to the accompanying drawings, forming a part thereof.

In the drawings,

Figure 1 is a front elevational view showing my new design of a speaker housing.

Figure 2 is a side elevational view of the disclosure shown in Figure 1.

Figure 3 is a rear elevational view of the disclosure shown in Figure 1.

Figure 4 is a top plan view of the disclosure shown in Figure 1.

Figure 5 is a fragmentary sectional view of the rear member taken substantially on the section line 5—5 of Figure 3.

I claim:

The ornamental design for a speaker housing, as shown.

ROBERT F. POORMAN.
